UNITED STATES PATENT OFFICE.

WILLIAM E. KINERT, OF BLUFFTON, INDIANA.

BARREL-SWING.

SPECIFICATION forming part of Letters Patent No. 350,370, dated October 5, 1886.

Application filed June 30, 1886. Serial No. 206,722. (No model.)

To all whom it may concern:

Be it known that I, WILLIAM E. KINERT, a citizen of the United States, residing at Bluffton, in the county of Wells and State of Indiana, have invented a new and useful Improvement in Barrel-Swings, of which the following is a specification.

My invention relates to an improvement in barrel-swings adapted to support the barrel under the counter, out of the way, and permit the same to be swung outwardly therefrom when it is desired to withdraw the contents of the barrel; and it consists in the peculiar construction and combination of devices, that will be more fully set forth hereinafter, and particularly pointed out in the claims.

In the drawings, Figure 1 is a perspective view of a barrel-swing embodying my improvement. Fig. 3 is a vertical sectional view of the same. Fig. 2 is a horizontal section taken on the line xx of Fig. 3.

A represents a vertical spindle or standard, which is provided at its lower end with a plate, B, by means of which the said standard may be secured firmly to the floor under the counter of a store or warehouse. A collar, C, slides on the spindle A, and is provided with a set-screw, D, by means of which the collar may be secured to the spindle at any desired vertical adjustment.

E represents a rest or support which is provided with a central opening to receive the upper end of the spindle A. This rest is thus pivoted on the said spindle, and is provided on one side with projecting arms e, having recesses to receive the flange of the barrel below the bottom thereof. From the opposite side of the rest extends an arm, e', which is provided with a vertical opening or slot, e².

F represents a vertical sliding bar, the lower end of which enters the opening e². To the upper end of the bar F is attached a horizontal arm, G, which is provided near its outer end, on its under side, with a series of ratchet-teeth, g. Through the center of the arm G, immediately over the center of the spindle A, is made an opening, g'.

H represents a plate or casting, which is provided on its under side with a depending

hollow stud, h', having a threaded opening to receive a headed securing-screw, L. This plate H is secured to the under side of the counter in such a position that the stud h extends downwardly through the opening g' of the arm G, and exactly above the spindle A, so as to pivot the arm G to the under side of the counter immediately over the pivot of the rest E.

I represents a sliding catch or dog, which is provided with an opening, i, to receive the outer end of the arm G. The lower side of this opening is inclined, as at i', thereby forming a sharpened edge adapted to engage with either of the series of ratchet-teeth g. From the lower end of the dog I extends a flange or lip, i², which projects toward the rear end of the arm G. The barrel to be supported upon the swing has one edge of its lower side placed upon the rest E, and the dog I is caused to engage with the upper inner flanged head of the barrel in the manner well known.

It will be readily understood from the foregoing description that the barrel is thus supported in a vertically-pivoted frame, whereby the barrel may be swung outwardly from under the counter when it is desired to draw liquid therefrom, and moved inwardly under the counter, out of the way. By making the collar C adjustable on the spindle A, and adapting the bar F to slide up and down in the slot E² of the support E, the apparatus may be adjusted vertically, so as to adapt it to fit a barrel of any size.

Having thus described my invention, I claim—

1. In combination with the spindle A, the barrel-rest E, pivoted thereon, the collar C, for adjusting the rest vertically, the plate H, having stud or pivot h, the arm G, pivoted on the stud, and the bar F, connecting the arm G and barrel-rest on one side of their pivot-points, as set forth.

2. In combination with the pivoted barrel-rest E, the pivoted arm G, located above the barrel-rest, and the dog or detent I, sliding on the arm G and adapted to be held at various points of said arm, as set forth.

3. In combination with the pivoted barrel-rest E, the pivoted arm G above the barrel-rest and carrying the dog or detent, and the

arm F, connecting the arm G and barrel-rest on one side of the pivot-points thereof, as set forth.

4. The combination of the pivoted barrel-rest, having the opening e^2 , and the pivoted arm G above the barrel-rest, having the depending bar F, entering the opening e^2 , the barrel-rest being vertically adjustable, substantially as described.

to 5. The combination, in a barrel-swing, of the pivoted arm G, having the ratchet-teeth g , and

the sliding dog I, engaging with the said teeth, for the purpose set forth, substantially as described.

In testimony that I claim the foregoing as 15 my own I have hereto affixed my signature in presence of two witnesses.

WM. E. KINERT.
